UNITED STATES PATENT OFFICE.

DAVID J. POWERS, OF CHICAGO, ILLINOIS, ASSIGNOR TO THE UNION WIRE MATTRESS COMPANY, OF SAME PLACE.

BED-SPRING.

SPECIFICATION forming part of Letters Patent No. 671,233, dated April 2, 1901.

Application filed August 17, 1900. Serial No. 27,170. (No model.)

To all whom it may concern:

Be it known that I, DAVID J. POWERS, of Chicago, in the county of Cook and State of Illinois, have invented certain new and useful Improvements in Bed-Springs, of which the following is a specification.

This invention relates to improvements in bed or mattress springs, and refers more specifically to an improved construction in the underlying supporting-frame upon which the springs are mounted, embracing as its most salient feature a novel and improved construction in the means whereby the springs are attached to said frame and the frame members made rigid with each other.

The object of the invention is to provide a simplified and improved construction of the character referred to; and the invention consists in the matters hereinafter described, and more particularly pointed out in the appended claim.

The invention will be more readily understood by reference to the accompanying drawings, in conjunction with the description, wherein—

Figure 1 is a top plan view of a portion of a bed-spring embodying my invention, and Fig. 2 is a vertical sectional view taken on line 2 of Fig. 1.

Referring to said drawings, 1 designates an outer marginal frame, which may be of any suitable construction, as shown herein being formed of strap-iron arranged with its plane vertical, as shown.

2 designates the several members of a series of supporting cross bars or strips, formed of strap-iron, the main intermediate portions of which are disposed with their planes vertical, while the end portions 3, whereby they are attached to the marginal frame members 1, are desirably each provided with a quarter-turn twist extended vertically upward adjacent to the side of the approximate frame member and riveted thereto, as indicated at

4, the extreme end portions being turned horizontally outward to form supports 5, whereby the bed-spring as a whole is supported upon the bedstead. It is to be understood that the particular construction whereby the supporting bars or strips 2 are united with the marginal frame is immaterial so far

as the invention is concerned, the present construction being desirable, however, for the reason that it is not only cheap and reliable, but also serves to support the main body of 55 the cross-strip somewhat below the level of the marginal frame, so that the latter in part surrounds or incloses the set of springs and at the same time reduces the height to which the upper surface of the set of springs extends above the point of supporting attachment with the bedstead. The several supporting-strips 2 of the series are desirably arranged parallel with each other and at a distance apart corresponding to the distance at 65 which it is desired to arrange the several springs.

6 designate the several members of a series of stay-strips arranged to extend transversely to the series of supporting cross-strips 2, said stay-strips being also constructed of strap-iron, but arranged with their planes horizontally. The strips 6 are also connected at their ends with the marginal frame 1 in any suitable manner, in the present instance by being looped around the latter, as indicated at 7, and are arranged parallel with each other and at a distance apart equal to the distance between the several coils of the bed-spring. These stay-strips 6 are so disposed that their main intermediate portions occupy a plane located intermediate of the upper and lower margins of the supporting cross-strips, and at each point of intersection with said supporting-strips said 80 stay-strips are provided with upwardly-bent flat loops or bends 9, which embrace the upper margins of the respective supporting-strips, the length or depth of these loops being equal to the distance at which the main body of the stay-strip is located below the upper edge of the supporting cross-strips, so that the upper end of each loop rests in direct bearing with the upper margin of the cross-strip it engages.

10 designate the several coil-springs of the series, these being of the usual cone-shaped construction, so far as their general shape is concerned. In order to secure the lower end of each of said coil-springs 10 to the supporting-frame, constructed as described, in such manner as to not only form a reliable

means of attaching the coil to the frame, but at the same time to lock or bend the supporting and stay strips positively together, I adopt a peculiar interlocked construction, 5 which is arranged as follows: The several springs 10 are so located that their several vertical axes substantially coincide with the points of intersection of the supporting and stay strips, the smaller end of the coil being 10 arranged downwardly, and the lowermost turn or coil 11 of each spring is passed around the upstanding loop portion 9 of the stay-strip and arranged to rest directly upon the upper surface of the latter. In order to permit the 15 coil to thus encircle said loop portion and rest upon the adjacent upper surface of the stay-strip, the cross supporting-strip 2 is provided at each side of the stay-strip with an aperture, as 12 13, which are located in a horizontal plane substantially coincident with 20 the upper surface of the main body of the stay-strip, so that the engagement of the coil 11 of the spring therewith in the manner described serves to positively lock the stay-strip 25 and the cross supporting-strip to each other. The upper ends of the several springs are suitably connected with any preferred floating frame or network, that shown herein comprising a marginal frame 14, to which is attached 30 a network or skeleton wire frame composed of a plurality of parallel bars or wires 15, united with each other and the subjacent springs by means of interlocking cross-bars 16, arranged in a well-understood manner, as 35 shown clearly in the drawings. It is to be noted, however, that the connection of the upper ends of the several coil-springs with the floating frame will be such as to prevent said springs from rotating upon their vertical 40 axes, thereby preventing the disengagement of their lower coils from the underlying supporting-frame.

It will be understood from the foregoing description that a construction embodying 45 my invention is extremely simple and economical to manufacture, all special secur-

ing devices of whatsoever nature for uniting supporting-frame members with each other and the several springs to the supporting-frame being entirely dispensed with and these 50 parts securely united by the simple expedient of interlocking the lower end of the spring itself with said members in the manner described. At the same time a supporting-frame constructed as described is extremely strong and rigid. The parts thereof 55 are so interlocked as to prevent one contacting part from moving upon another, thereby avoiding creaking, and the peculiar arrangement of the stay-strips affords a broad and 60 level supporting-surface upon which the lower end of the active part of the spring is supported. The structure is also one which may be readily dismantled or separated either for the purpose of replacing or repairing the 65 springs.

I claim as my invention—

In a bed-spring, the combination of a series of flat supporting-bars, arranged with their planes vertical, a series of transverse 70 intersecting metal stays, each provided at its points of intersection with the supporting-bars with a loop arranged to overlie and rest upon the upper edge of the supporting-bar, said supporting-bars having a series of apertures formed therethrough in a plane substantially coincident with the upper surface of the main body of the stay member at each side of the loop thereof, and a series of coiled springs, each connected with said supporting-frame by having its lowermost turn or coil passed through said apertures and arranged to rest upon said upper surface of the stay-bar whereby the supporting-bar and stay member are locked in fixed relation with each 75 other and the spring is thus united with the supporting members, substantially as described.

DAVID J. POWERS.
